DESIGN FOR A CROQUET MALLET

Jacob Pressman, New York, N. Y.

Application December 6, 1940, Serial No. 97,107

Term of patent 7 years

To all whom it may concern:

Be it known that I, Jacob Pressman, a citizen of the United States and a resident of the city of New York, Borough of Manhattan, in the county and State of New York, have invented the new, original, and ornamental Design for a Croquet Mallet, of which the following is a specification, reference being had to the accompanying drawing, forming part thereof, in which—

Fig. 1 is a perspective view of the croquet mallet showing my design; and

Fig. 2 is a side view of the croquet mallet, the opposite side of the device being similar in appearance.

I claim:

The ornamental design for a croquet mallet, substantially as shown and described.

JACOB PRESSMAN.
